MEANS FOR FILLING AND SEALING A VESSEL

Filed Aug. 29, 1932

UNITED STATES PATENT OFFICE

2,022,656

MEANS FOR FILLING AND SEALING
A VESSELTitan D. Du Plantier, Brooklyn, N. Y., assignor of
one-fourth to Arthur Ladson, New York, N. Y.

Application August 29, 1932, Serial No. 630,911

8 Claims. (Cl. 226—73)

The present invention relates to a method and apparatus for filling and sealing a vessel, such as a bottle or the like.

More particularly, my invention concerns the ready evacuation of the vessel to be filled, the insertion of its intended contents thereinto, and the affixing of a suitable seal thereto. Preferably this seal is designed of a waxy composition, having a comparatively low melting point. This sealing composition is usually maintained in a heated, fluid condition and is applied in that form to the filled bottle, where in the preferred form, it is rapidly chilled and solidified by external cooling means. Preferably, the sequence of operations, (evacuating, filling, and sealing), is controlled by a single instrumentality.

One object of my invention therefore, is to provide a single apparatus for evacuating, filling, and sealing a vessel.

Another object is to produce a new method of evacuating, filling, and sealing a vessel.

Another object is to produce a multi-part apparatus for evacuating, filling, and sealing a vessel.

Another object is to produce a substantially one-piece apparatus for evacuating, filling, and sealing a vessel.

Another object is to produce an apparatus having a single means for controlling the evacuating, filling, and sealing of a vessel.

Another object is to produce a method of controlling from a single station, the evacuating, cooling, and sealing of a vessel.

Another object is to produce an apparatus for evacuating, filling, and sealing a vessel, wherein the sealing material is maintained in fluid condition until applied to the vessel, and is then rapidly chilled and solidified.

Yet another object is to produce a method for maintaining a sealing material molten, controlling from a single station the evacuation, and filling of a vessel and application thereto of the molten sealing material, and passing a cooling fluid about the sealing material so applied, to rapidly chill and solidify the same.

Other objects and advantages will be more fully developed hereinafter.

One form of my invention is described hereinafter, merely by way of example, with reference to the attached drawing, wherein is shown, in sectional plan, one form of the said apparatus.

The apparatus is shown as comprising an outer body portion or casing 1, to which may be threaded or otherwise secured at the upper end 2, a cap or head portion 3; and in similar manner at its

lower end 4, a base member 5 is secured, adapted for the reception of the neck of the vessel (usually a bottle) to be filled. These parts are preferably provided of glass, or other inactive insulating material, but of course may also be provided of any other suitable material. Preferably, a sealing washer or gasket 41 is provided between the lower end 4 of the housing 1 and the upper end of the base member 5, in order to ensure a liquid tight joint therebetween. It is further to be understood that while a multi-part construction has been disclosed, to facilitate ready dismantling and cleaning, it is equally within the province of the invention to form the apparatus casing of a single piece, and to rely upon other methods of cleaning.

Approximately at its center, the cap 3 is preferably provided with an inturned depending and threaded flange 6, which is shown as receiving a so-called sealing compound inlet 7, the purpose of which will be more fully described hereinafter.

In the construction shown, the skirt 8 of the inlet 7 extends beyond the edge of the rim 6, and is threaded throughout its length, to receive the correspondingly threaded throat 9 of the chamber 10, adapted to receive the sealing compound. This chamber 10, as in fact are nearly all of the other parts to be described hereinafter, except as specifically noted to the contrary is preferably formed of glass; but it is obvious that it may also be made of any other suitable material.

The base portion 5 is preferably provided with a gasket 11 to resiliently receive the neck of a vessel to be filled, while a rim 12 of rubber or the like material is provided for a similar purpose. Because of its hollow construction, the base 5 is provided with an annular recess or chamber 13, and in the preferred instance is provided with at least one inlet and outlet 14 and 15, for the circulation of a cooling fluid, the purpose of which will be explained hereinafter, in greater detail.

Broken into the wall of the chamber 1 at 16, or secured thereto in any other desired manner or location, is a tubular member 17, adapted to be connected at its outer end to a vacuum pump, not shown, and at its inner end, through a stop cock to be more fully described, to a passage 18.

At its lower end, the sealing compound chamber 10 is threaded to a nipple 19, provided on an inturned portion of the casing 1, and having a passage 20, connecting through another port of the said stop cock, with a passage 21 ex-

tending just short of the neck of the vessel to be filled.

A third passage 22 extends annularly about the passage 21, and terminates short thereof, 5 for reasons to be more fully explained. Thus passage 22, at its upper end, communicates with the said passage 18, and with another passage 23, which last-mentioned passage, through still another port in the stop cock, communicates with 10 a passage 24, likewise broken into the wall of the casing 1, and leading to the supply of filling material, not shown.

It will be noted that the casing 1 and chamber 10 provide between them a somewhat annular-shaped recess 25, having an inlet 26 and an outlet 27, for the circulation of a heating fluid past the chamber 10 and passages 20 and 21, to maintain the sealing material in fluid condition.

20 Located in any desired manner in the casing 1, a seat 28 is provided for the reception of a three-way stop cock 29, having ports 30, 31, and 32. The casing is shown as having a flange 33 adjacent to and forming a continuation of the 25 seat 28 for the stop cock, and this flange is preferably threaded to receive a cap 34. The stop cock proper terminates in a shoulder 35 from which extends a stem 36, having a still further portion 37, of reduced diameter, passing through 30 the cap 34, and terminating in a handle 38. Between the shoulder 35 and the inner surface of the cap 34, a compression spring 39 is provided about the stem 36, tending to constantly urge the stop cock into its seat, so that it can be rotated only against the energy of the spring and continuously provide a perfect seal.

The operation of the apparatus is somewhat as follows:—

The vessel to be filled is placed in position 40 in the opening 48 provided in the base 5, against the gasket 11 and rubber edge 12. The passage of cooling fluid through the recess 13 is started. Sealing material previously has been stored in the chamber 10, through the inlet 1, and this 45 material is maintained in fluid condition by the circulation of heating fluid through the recess 25, entering at 26 and exiting through 27. The stop cock is now turned so that the port 30 connects the passages 17 and 18, all the other ports 50 being closed. At this time the vessel, through ports 22, 18, bore 38, and port 17, is connected to a vacuum pump, and is rapidly evacuated.

Following the evacuation step, the stop cock is rotated until the port 32 connects the passages 23 and 24, thus establishing a communication between the vessel, the passages 22 and 23, the port 32, and the passage 24 to the source 55 of filling material for the vessel, the other ports of the stop cock being closed.

60 The vessel now being filled, the stop cock is still further rotated until, the other ports being closed, the port 31 connects the chamber 10, through passage 20, port 31 and passage 21, with the vessel, so that fluid sealing material flows 65 onto the surface of the filling material in the vessel, where, under action of the cooling fluid in the recess 13, it is rapidly chilled and solidified.

It is to be noted that the passage 21 is longer 70 than the surrounding passage 22. Experience has shown that if this condition does not exist, and the passages terminate in the same plane, some of the sealing material will be sucked into the passage 18.

75 While only a single, three-way cock has been

shown, it is obvious that three separate cocks may be employed, if so desired.

While only a waxy-like sealing material has been disclosed, it is readily evident that any sealing material, suitable to the particular conditions, 5 and characterized by the fact that it has a low melting point and is solid at normal temperatures, may be employed. Among such materials, merely by way of example are the following: "Khotinsky" cement, paraffin, artificial resins 10 such as "Bakelite", sealing cement, gelatin, "Duco sealing cement", and "Parker-Davis sealing cement".

It is obvious that, once my invention has been disclosed in the broad aspects, numerous modifications and adaptations falling within the province of the invention will readily suggest themselves to those skilled in the art. Accordingly, it is intended that my invention be limited only by the scope of the appended claims. 20

I claim:—

1. An apparatus for filling and sealing a vessel, comprising connections to an evacuating means, connections to a source of filling material, a source of liquid sealing material, means for interconnecting the connections to the evacuating means and the vessel, to evacuate the latter, means to interconnect the connections to the source of filling material and the vessel, to fill the latter, and means to connect the source of sealing material and the vessel, to supply sealing material thereto, each of said means consisting in part of a discharge orifice common to all three means and adapted to connect with said vessel. 25

2. An apparatus for filling and sealing a vessel, 30 comprising connections to an evacuating means, connections to a source of filling material, a source of liquid sealing material, means for interconnecting the connections to the evacuating means and the vessel, to evacuate the latter, means to interconnect the connections to the source of filling material and the vessel, to fill the latter, means to connect the source of sealing material and the vessel, to supply sealing material thereto, each of said means consisting in part of a discharge 35 orifice common to all three means and adapted to connect with said vessel, and means for heating said sealing material to liquid condition, prior to insertion in said vessel. 40

3. An apparatus for filling and sealing a vessel, 45 comprising connections to an evacuating means, connections to a source of filling material, a source of liquid sealing material, means for interconnecting the connections to the evacuating means and the vessel, to evacuate the latter, 50 means to interconnect the connections to the source of filling material and the vessel, to fill the latter, means to connect the source of sealing material and the vessel, to supply sealing material thereto, means for heating said sealing 55 material in said source thereof to liquid condition, and means disposed externally of the neck of the vessel, for cooling and solidifying the liquid sealing material inserted therein. 60

4. An apparatus for filling and sealing a vessel, 65 comprising connections to an evacuating means, connections to a source of filling material, a source of liquid sealing material, separate means interconnecting each of the connections of said evacuating means, the connections of said source of filling, and said source of sealing material to said vessel, and a single means for effecting said connections, one at a time, while maintaining the other connections interrupted, to successively 70 evacuate, fill, and seal said vessel. 75

5. An apparatus for filling and sealing a vessel, comprising connections to an evacuating means, connections to a source of filling material, a source of liquid sealing material, separate means 5 interconnecting each of said connections to said evacuating means, said connections to said source of filling material, and said source of sealing material to said vessel, said separate means each consisting in part of a discharge orifice common 10 to all of said separate means and adapted to connect with said vessel, and means for maintaining said sealing material in liquid condition prior to insertion in said vessel, said vessel being successively evacuated, filled, and sealed.
- 15 6. A unitary vessel-filling and sealing apparatus comprising an outer casing, a chamber disposed therein and adapted to receive a liquid sealing material, means defining passages extending through said casing and adapted to be connected respectively to evacuating means and a source of filling material for the vessel, a three-way stop cock disposed in said casing having ports communicating one with each of said chamber and said passage-forming means, means at 20 the bottom of the casing to which the vessel to be filled is fitted, and means defining additional passages communicating between the vessel and the ports of the stop cock, whereby the vessel may be connected at will directly either to the chamber or to either of the two first-mentioned 25 passages, to the exclusion of the others.
- 25 7. A unitary vessel-filling and sealing apparatus comprising an outer casing, a chamber disposed therein and adapted to receive a liquid sealing material, means defining passages extending through said casing and adapted to be connected respectively to evacuating means and a source of filling material for the vessel, the 30
- casing and the chamber forming between them a recess for the passage of fluid to heat the sealing material to liquid consistency, inlet and outlet means on the casing for the passage of said heating fluid, a three-way stop cock disposed in said casing having ports communicating one with each of said chamber and said passage-forming means, means at the bottom of the casing to which the vessel to be filled is fitted, and means defining additional passages communicating between the vessel and the ports of the stop cock, whereby the vessel may be connected at will directly either to the chamber or to either of the two first-mentioned 35 passages, to the exclusion of the others, said means at the bottom of the casing having a recess disposed therein for the passage of a cooling fluid, to cool and solidify the liquid sealing material after the latter has been inserted on the filled vessel.
8. A unitary vessel-filling and sealing apparatus comprising an outer casing, a chamber disposed therein and adapted to receive a liquid sealing material, means defining passages extending through said casing and adapted to be connected respectively to evacuating means and a source of filling material for the vessel, a three-way stop cock disposed in said casing having ports communicating one with each of said chamber and said passage-forming means, means at the bottom of the casing to which the vessel to be filled is fitted, and means defining additional passages communicating between the vessel and the ports of the stop cock, whereby the vessel may be connected at will directly either to the chamber or to either of the two first-mentioned 30 passages, to the exclusion of the others, the said parts of the apparatus being formed of glass.

TITAN D. DU PLANTIER.
